UNITED STATES PATENT OFFICE.

WILLIAM W. JACKSON, OF CHICAGO, ILLINOIS, ASSIGNOR OF ONE-FOURTH
TO WILLIAM B. LA PARLE, OF SAME PLACE.

WRENCH FOR BUNG-BUSHINGS.

SPECIFICATION forming part of Letters Patent No. 268,408, dated December 5, 1882.

Application filed September 29, 1882. (No model.)

To all whom it may concern:

Be it known that I, WILLIAM W. JACKSON, brewer and maltster, a citizen of the United States, residing in Chicago, in the county of Cook and State of Illinois, have invented certain new and useful Improvements in Wrenches for Bung-Bushings, of which the following is a specification.

My invention relates to wrenches for bung-bushings, in which an adjustable core removably and adjustably fitting in a bung-bushing is employed and adapted to be tightened in the bushing, and to be operated so as to screw the bushing to place in the barrel.

The objects of my invention are to provide a wrench with a core composed of a single piece, and adapted to be expanded in the bushing during the operation of screwing the bushing to place; to provide a wrench the core and core-tightening device of which are simultaneously tightened upon each other and the core tightened in the bung-bushing; to provide a wrench with an expandable core composed of a single piece and a tightening device operating in the core, so that when said device is tightened in the core the core will be correspondingly tightened in the bung-bushing, but will contract to substantially its normal condition when the tightener is relaxed and in condition to be readily withdrawn from the bushing; to provide a wrench with a core conforming to the bore of a bung-bushing and a corresponding tightening device fitting in said core, whereby the bushing may be maintained in its operative position while being set to place in a barrel; to provide a wrench with an expandable core the outer or gripping teeth of which are formed in one piece with the core; and, finally, to provide a wrench with a core adapted to grip or take hold of a bushing, and with a tightening device which, co-operating with the core and bung, has the functions of a compound screw, thereby lessening the amount of applied power otherwise required to set a bung-bushing in its operative position in a barrel. I attain these objects by devices illustrated in the accompanying drawings, in which—

Figure 1 is a side elevation of a wrench embodying my invention in its operative position in a bung-bushing, which bushing is shown in

cross-section; Fig. 2, a central longitudinal section of the same on the line *y* *y* of Fig. 3, and Fig. 3 a cross-section on the line *x* *x* of Fig. 1.

Similar letters of reference indicate the same parts in the several figures of the drawings.

A represents a hollow, concave, cone-shaped core, internally screw-threaded from end to end, and provided externally with a series of longitudinal teeth, *a*, at intervals of its periphery, which teeth serve to grip or take hold of the bung-bushing *B* when the core is tightened in the bung. This core is longitudinally slotted from end to end on one side, as shown at *b*, to permit the core to expand and contract, as hereinafter described, and at its top or base end of the cone is provided with a laterally-projecting flange, *c*, which prevents the core from slipping through a large-sized bushing, as it might otherwise do before the core could be expanded to grip the bushing. Fitting in this core is a tapering screw, *C*, which, having a larger diameter than the core, is tightened in the core when in the position relative thereto shown in Fig. 2, but which, when further tightened, expands the core and causes its teeth to grip the bushing, as shown in Fig. 3. This screw *C*, which is termed the "tightening device," is provided with a head, *D*, having formed therewith, or otherwise secured to it, handles *d* for convenience in steadyng the wrench and with it the bushing during the first part of the operation of setting the bushing; and before a longer lever, *E*, passing through an eye in the head, is required to finally tighten the bushing in its operative position in the barrel, it being understood that the bushing is provided with an external screw-thread which must be forced with considerable power to cut a corresponding screw-thread in the barrel, so that when the bushing is forced to place it cannot possibly be accidentally detached. The core, and with it the tightening-screw, is made of a sufficient length to adapt it for operating a considerable number of varying sizes of bushings, the inclination of the core being such as to conform to and have a solid bearing against the inclined inner faces of such varying sizes of bushing.

The operation of the wrench is very clearly illustrated on the medium-sized bushing shown

in Fig. 2, wherein the wrench is shown in its operative position in the bushing after the bushing is set. If the bushing were in position to be set, the wrench would be in substantially the same position, but the tightener a little farther up in the core, when by steadyng the wrench by means of its handles while turning them the bushing would also be steadied and given a proper start in the barrel by reason of the core tightening in the bushing and the screw tightening in the core, so that in fact the handles of the wrench are in effect handles to turn the core. As the resistance of the bushing increases the power to the handles is increased. Hence the screw correspondingly tightens in the core, and, expanding it, increases the force of the grip of the core corresponding with the resistance of the bushing, and, as will be understood, the power of the wrench and its operation in the bushing relative to the barrel are that of a compound-screw. When the resistance of the bushing is too great for convenience in using the handles a longer leverage is obtained by employing the rod or lever E, passed through the eye in the head, the bushing by this time having secured sufficient hold to maintain itself perpendicular to the barrel. In this connection it may be stated that the core is never necessarily detached from the screw-tightener, and that when the diameter of the bushing corresponds with or is a little larger than the largest diameter of the core the flange c will rest on the bushing when the core is inserted until the tightener has been operated to expand the core and grip the bushing.

Instead of a flange, c, projections or other suitable devices may be employed. So, also, the form of the gripping-teeth a may be varied; or

they may be on detached plates dovetailed or otherwise secured to the core without departing from the spirit of my invention.

This wrench recommends itself for the simplicity and cheapness of its construction, and for the almost unlimited power it embodies and the absence of small detachable pieces liable to be worn out or lost.

Having thus described my invention, what I claim, and desire to secure by Letters Patent, is—

1. The combination, with an expansible core composed of a single piece and provided with internal screw-threads, of a correspondingly screw-threaded tightener fitting in and adapted to expand said core, substantially as described.

2. The combination, with a hollow truncated cone shaped expansible core provided with internal screw-threads, of a tapering screw-tightener operating in and adapted to expand said core, substantially as and for the purpose described.

3. The combination, with the internally-screw-threaded expansible core, of a tapering screw-threaded tightener operating in said core, and provided with the rigid and short levers d d and with a removable long lever, substantially as described.

4. In a bung-bushing wrench, a hollow truncated cone-shaped core adapted to be fitted in the bushing, and provided with a single longitudinal slot extending from end to end, and with a flange on its upper and base end, substantially as and for the purpose described.

WILLIAM W. JACKSON.
